UNITED STATES PATENT OFFICE

135,859

DESIGN FOR A PORTABLE HEATER UNIT

Donald H. Powers, Tacoma, Wash.

Application January 19, 1942, Serial No. 105,300

Term of patent 14 years

To all whom it may concern:

Be it known that I, Donald H. Powers, a citizen of the United States, residing at Tacoma, in the county of Pierce, in the State of Washington, have invented a new, original, and ornamental Design for a Portable Heater Unit, of which the following is a specification, reference being had to the accompanying drawing forming part thereof.

Figure 1 is a front and side perspective view of a portable heater unit showing my new design, and

Figure 2 is also a perspective view showing the rear and other side.

I claim:

The ornamental design for a portable heater unit, substantially as shown.

DONALD H. POWERS.
